1

This invention relates to the manufacture of hydroxy compounds by the hydrogenative splitting of vicinal epoxides, i. e. epoxides containing the grouping

It is known that in the reduction of vicinal epoxides difficulties are often encountered which in most cases consist in that non-uniform reaction products are formed. Moreover, in the case of difficultly hydrogenatable vicinal oxido-bridges, the expectation is that under the energetic reaction conditions employed the oxido-oxygen may be completely eliminated.

Synthetic processes for the manufacture of hydroxy compounds, in particular for the introduction of single hydroxy groups into the structure of steroids, are already known and among these processes splitting by reduction of oxido-compounds is occasionally encountered. In the case of the steroids, there are primarily involved those of the sexual and suprarenal hormone series and also numerous representatives of the strophanthus, digitalis, scilla, toad venom and cardiac poisons which contain hydroxyl groups at certain positions of the cyclopentanopolyhydrophenanthrene structure, which hydroxyl groups are of importance for the physiological properties of the mentioned compounds. The hitherto known methods of reductive splitting of oxides lead, however, to the desired result, only in quite a limited number of cases.

Thus, for example, it has not been possible by reduction of $4\beta,5$ -oxido- $5,6\beta$ -oxido-steroids to arrive at 5 -hydroxy-coprostan derivatives which correspond in configuration, for example, to strophanthidin and until now no synthesis has become known which leads in this manner to derivatives of 5 -hydroxy-coprostan. The β -oxides of allocholesterol and of epi-allo-cholesterol, for example, yield $3,4$ -dihydroxy-cholestanes on catalytic reduction.

It has also hitherto not been possible, by reduction of $16,17\alpha$ -oxido-steroids, the configuration of which at the C-atoms 16 and 17 has moreover not yet been established, to produce 17α -hydroxy compounds which correspond to the natural 17 -hydroxy-steroids of the suprarenal hormone series. In other cases it is true that it has been possible to realize the reductive splitting of the oxides in the desired direction, but the yields produced were often low and mixtures of isomers were produced which were difficult to

2

separate. Whereas $11\beta,12\beta$ -oxido compounds of the cholic acid series likewise yielded mixtures on reduction, the 3α -acetoxy- $9,11$ -oxido-cholic acid methyl ester was hardly affected at all by catalytically activated hydrogen.

A primary object of the present invention is the realization of the reductive splitting of those steroid epoxides which have hitherto withstood other reduction methods, such as for example catalytic hydrogenation or reduction with sodium and alcohol.

This object, and others which will become evident as the disclosure of the invention is herein-after developed, is realized according to the present invention by the expedient of effecting the desired reductive splitting with the aid of reactive metal hydrides as the reducing agents. More particularly, use is made in this regard of the bimetal hydrides such as alkali metal-aluminum hydrides, and primarily of lithium-aluminum hydride, further also of sodium- or lithium-boron hydride. In this manner, it has been found that the oxido bridges in vicinal epoxides can be split by hydrogenation by way of a mild reaction which can be easily carried out in a uniform manner.

By means of the present process success has been achieved, in particular, in the reductive splitting of certain steroid epoxides which have hitherto withstood other reduction methods, such as those aforementioned.

The vicinal epoxides, serving as starting materials, belong to the steroid series, especially to the $10,13$ - dimethylcyclopentano - polyhydrophenanthrenes which may be substituted in any desired manner. The present process will be employed primarily, i. e. with especial advantage, in the case of $4,5$ -, $11,12$ -, $14,15$ -, $16,17$ -, and $20,21$ -steroid epoxides which could not hitherto be converted into the desired end products at all by customary methods or only in poor yield. Thus, the present process has made it possible to achieve for the first time the partial synthetic production of $3\beta,5$ -dihydroxycoprostan, starting from 3β -hydroxy- $4,5$ -oxido-cholestane and also the reduction, in smooth manner, of $16,17\alpha$ -oxido-steroids to 17α -hydroxy compounds and of $11,12$ -oxido-steroids to uniform hydroxy derivatives.

The reduction is advantageously carried out in the presence of a diluent which may vary according to the metal-hydride used. Thus, the reduction with an alkali metal-aluminum hydride, such as lithium-aluminum hydride, is effected in the presence of an indifferent anhydrous organic solvent in which the metal hydride is soluble, in particular in the presence of ether or also tetrahydro-

furan, butyl ether and the like. When working, for example, with sodium-boron hydride, the reduction is advantageously carried out in the presence of water.

The following examples illustrate the invention, the parts being by weight unless otherwise stated and the relationship of parts by weight to parts by volume being the same as that the kilogram to the liter:

EXAMPLE 1

*3 β ,17 α ,20 β -trihydroxy-5-*allo*-pregnane (Reichstein's Substance J), 3 β ,20 β -diacetoxyl-17 α -hydroxy-5-*allo*-pregnane (Reichstein's Substance J-diacetate) and 3 β ,20 α -diacetoxyl-17 α -hydroxy-5-*allo*-pregnane (Reichstein's Substance O-diacetate) of the formulae*

7 parts of 3 β -acetoxyl-16,17 α -oxido-20-keto-5-*allo*-pregnane of melting point 181° C. (produced, for example, by reaction of Δ^{16} -3 β -acetoxyl-20-keto-5-*allo*-pregnane with perbenzoic acid or hydrogen peroxide in glacial acetic acid) are dissolved in 300 parts by volume of absolute ether and added drop by drop with good stirring to a solution of 4 parts of lithium-aluminum hydride in 600 parts by volume of dry ether. When the fairly vigorous reaction has subsided, the solution is heated to boiling for another hour, and then water and finally dilute sulfuric acid are carefully added thereto. The ethereal layer is washed neutral with water, dried and evaporated. The crystallized residue can be purified by recrystallization from methanol-water and then melts at 223-224° C. It consists of 3 β ,17 α ,20 β -trihydroxy-5-*allo*-pregnane (Substance J of Reichstein, 1938).

From the mixture of the mother liquors, by acetylation and chromatographic purification, the following 17 α -hydroxy-steroids can be isolated: 3 β ,20 β -diacetoxyl-17 α -hydroxy-5-*allo*-pregnane of melting point 161° C. (Substance J-diacetate of Reichstein) and 3 β ,20 α -diacetoxyl-17 α -hydroxy-5-*allo*-pregnane of melting point 243° C. (Substance O-diacetate of Reichstein, 1938).

In the same manner, 3 β -hydroxy-16,17 α -oxido-20-keto-5-*allo*-pregnane of melting point 181-182° C., unesterified in position 3, reacts with lithium-aluminum hydride in ether. The reac-

tion products are again Reichstein's Substances J and O.

EXAMPLE 2

*3 β ,17 α ,20,21-tetrahydroxy-5-*allo*-pregnane (Reichstein's Substance K) of the formula*

In the same manner as that set forth in Example 1, 3 β ,21-diacetoxyl-16,17 α -oxido-20-keto-5-*allo*-pregnane of melting point 153-154° C. can be reacted with lithium-aluminum hydride. The product of this reaction is 3 β ,17 α ,20,21-tetrahydroxy-5-*allo*-pregnane (Reichstein's Substance K) of melting point 198-200° C.

Other pregnanes which contain other acyloxy groups or which are substituted by free hydroxyl groups instead of the esterified hydroxyl groups may also be subjected to a similar reduction.

EXAMPLE 3

3 β ,5-dihydroxy-coprostanone of the formula

7 parts of 3 β -acetoxyl-4 β ,5-oxido-coprostanone of melting point 89° C. (produced by catalytic hydrogenation of 3-keto-4 β ,5-oxido-coprostanone and subsequent acetylation or, preferably, by oxidation of Δ^4 -3 β -acetoxyl-cholestene with per-acids) are dissolved in 200 parts by volume of absolute ether and added drop by drop with good stirring to a solution of 5 parts of lithium-aluminum hydride in 500 parts by volume of dry ether. The reaction mixture is thoroughly stirred for 15 minutes and then 200 parts by volume of water and finally 400 parts by volume of 10 percent sulfuric acid are added drop by drop. After the addition of more ether, the ethereal layer is separated, washed neutral with water, dried and evaporated. The crystallized residue, after being twice recrystallized from ethanol, is obtained pure and melts at 148-149° C. It consists of 3 β ,5-dihydroxy-coprostanone. The 3-mono-acetyl derivative of this substance melts at 80-81° C.

In the same manner, 3 β -hydroxy-4 β ,5-oxido-coprostanone, unesterified in position 3, of melting point 95-96° C. can be reacted with lithium-aluminum hydride to form 3 β ,5-dihydroxy-coprostanone.

EXAMPLE 4

3 α ,5-dihydroxy-coprostanone of the formula

5 parts of 3α -acetoxy- $4\beta,5$ -oxido-coprostanate of melting point 68-70° C. (produced by hydrogenation of 3 -keto- $4\beta,5$ -oxido-coprostanate and subsequent acetylation or, preferably, by oxidation of $\Delta^4-3\alpha$ -acetoxy-cholestene with per-acids) are dissolved in 200 parts by volume of absolute ether and added drop by drop with good stirring to a solution of 5 parts of lithium-aluminum hydride in 500 parts by volume of dry ether. The reaction mixture is worked up as described in the preceding examples. The crystallized crude product is, after being twice recrystallized from methanol, obtained in the pure condition and melts at 192-193° C. It constitutes $3\alpha,5$ -dihydroxy-coprostanate. The 3 -mono-acetyl derivative of this substance melts at 147-148° C.

EXAMPLE 5

 $3\alpha,5$ -dihydroxy- and $3\beta,5$ -dihydroxy-coprostanate

5 parts of 3 -keto- $4\beta,5$ -oxido-coprostanate of melting point 116-117° C. (produced by oxidation of cholestenone with alkaline hydrogen peroxide) are dissolved in 200 parts by volume of absolute ether and added drop by drop with good stirring to a solution of 5 parts of lithium-aluminum hydride in 500 parts by volume of dry ether. The working up of the reaction mixture takes place as in the preceding examples. For purification the crude product is subjected to chromatographic procedures. In this manner the isolation is achieved of 3.5 parts of $3\alpha,5$ -dihydroxy-coprostanate of melting point 192-193° C. (see Example 4) and 1.3 parts of $3\beta,5$ -dihydroxy-coprostanate of melting point 148-149° C. (see Example 3).

EXAMPLE 6

 $3\beta,5$ -dihydroxy-cholestane of the formula1 part of α -cholesterol oxide acetate of melting point 92-95° C. is dissolved in 500 parts by volume of absolute ether and added drop by drop with good stirring to a solution of 1 part of lithium-aluminum hydride in 150 parts by volume of dry ether. The reaction solution is heated for 15 minutes to boiling, then drop by drop 100 parts by volume of water and finally 100 parts by volume of 10 per cent. sulfuric acid are added. The ethereal solution is washed neutral with water, dried and evaporated. The crystalline residue can be purified by recrystallization from ethyl acetate and then melts at 216-217° C. It constitutes $3\beta,5$ -dihydroxy-cholestane.

EXAMPLE 7

 $3\beta,6\beta$ -diacetoxy-cholestane of the formula4 parts of β -cholesterol oxide acetate of melting point 109° C. are dissolved in 500 parts by volume of absolute ether and added drop by drop with good stirring to a solution of 4 parts of lithium-aluminum hydride in 600 parts by volume of dry

ether. The working up of the reaction solution takes place as in Example 6. For further purification the $3\beta,6\beta$ -dihydroxy-cholestane is converted in known manner into the diacetate and this separated from by-products by adsorption on aluminum oxide. In this manner is achieved the isolation of 2.5 parts of pure $3\beta,6\beta$ -diacetoxy-cholestane of melting point 130-131° C.

EXAMPLE 8

 3α -hydroxy-cholestane and $2,3$ -dihydroxy-cholestane of the formulaeand

10 parts of $2,3\alpha$ -oxido-cholestane of melting point 105° C. are dissolved in 100 parts by volume of absolute ether, and to the resultant solution is added with stirring a solution of 2 parts of lithium-aluminum hydride in 300 parts of absolute ether. After the addition, the whole is further stirred for 40 minutes longer and heated for a further 10 minutes. The reaction mixture is treated with water, then with dilute sulfuric acid and extracted with ether. By chromatographic purification, 8 parts of 3α -hydroxy-cholestane and 1.5 parts of $2,3$ -dihydroxy-cholestane are isolated.

EXAMPLE 9

 2β -hydroxy-cholestane of the formula3 parts of $2,3\beta$ -oxido-cholestane of melting point 85° C. are dissolved in 300 parts by volume of absolute ether and treated drop by drop with good stirring with a solution of 2 parts of lithium-aluminum hydride in 300 parts by volume of anhydrous ether. The working up takes place as in Example 6. By recrystallization of the crude product, 2.5 parts of 2β -hydroxy-cholestane of melting point 152° C. are obtained.

EXAMPLE 10

 $3\alpha,5$ -dihydroxy-cholestane of the formula10 parts of 3α -hydroxy- $5,6\alpha$ -oxido-cholestane of melting point 122° C. are dissolved in 250 parts by volume of absolute ether, and 5.5 parts of lithium-aluminum hydride in 300 parts by volume of dry ether are added drop by drop with stirring. Working up as in Example 6 yields 8 parts of $3\alpha,5$ -dihydroxy-cholestane of melting point 180° C.

7

EXAMPLE 11

3 α ,5-dihydroxy-coprostanone and 3 α ,6-dihydroxy-cholestane of the formulae.

and

To 9 parts of 3 α -hydroxy-5 β -oxido-coprostanone of melting point 160-163° C. in 150 parts of absolute ether is added a solution of 4.5 parts of lithium-aluminum hydride. After an hour the reaction mixture is worked up as described in Example 6. By chromatographic purification, 1 part of 3 α -hydroxy-cholestane, 2 parts of 3 α ,5-dihydroxy-coprostanone and 5 parts of 3 α ,6 β -dihydroxy-cholestane are isolated.

EXAMPLE 12

3 parts of 3 α -acetoxy-11,12 β -oxido-cholanic-acid-methyl ester of melting point 150-154° C. are dissolved in 1000 parts by volume of anhydrous ether, and the resultant solution added dropwise and with thorough stirring to a solution of 8 parts of lithium-aluminum hydride in 1000 parts by volume of absolute ether. The reaction mixture is worked up as in Example 6. The obtained product, after recrystallization from ethyl acetate, melts at 186-188° C. and is identical with the reduction product of 3 α -acetoxy-11 β -hydroxy-cholanic-acid-methyl ester (melting point 146° C.) with lithium-aluminum hydride. The substance constitutes a triol and yields a crystallized diacetate and dibenzoate. The reduction is advantageously carried out in tetrahydrofuran or dioxane at a raised temperature in lieu of ether.

EXAMPLE 13

2 parts by weight of 3 α -acetoxy-11,12 α -oxido-cholanic-acid-methyl ester of melting point 141° C. are dissolved in 180 parts by volume of dry ether, the solution added dropwise and with thorough stirring to a solution of 2.2 parts of lithium-aluminum hydride in 120 parts by volume of absolute ether, and the reaction mixture worked up in the manner described in Example 6. The crystallized product, after recrystallization from a mixture of methanol and ethyl acetate, melts at 183-184° C. and is identical with the reduction product of 3 α ,11 α -diacetoxy-cholanic-acid-methyl ester and lithium-aluminum hydride. The substance constitutes a triol and may be characterized as such. As stated in Example 12, the reduction is advantageously carried out in tetrahydrofuran at a raised temperature.

Instead of the mentioned cholanic-acid methyl ester, there may be used other esters such as ethyl-, propyl- or butyl ester. Moreover, there may be used 11,12-oxido-cholanic acid esters containing a free hydroxy group instead of an acetoxy group in 3-position.

EXAMPLE 14

1 part of $\Delta^{16,17}$ -3 β -acetoxy-14,15 β -oxido-20-keto-5 α -allo-pregnene is dissolved in a mixture of

8

10 parts by volume of ether and 10 parts by volume of benzene, and the solution added dropwise and with thorough stirring to a solution of 1 part of lithium-aluminum hydride in 15 parts by volume of absolute ether. The reaction mixture is worked up as described in Example 6, and the crude product is adsorbed on 40 parts of aluminum oxide in order to purify the product. The benzene-ether eluates yield a compound which, after recrystallization from ether, melts at 174° C. and corresponds to the empirical formula C₂₁H₃₂O₃. A second substance of the formula C₂₁H₃₄O₃ is eluted with ether. It melts at 223-224° C., after recrystallization from ethyl acetate.

EXAMPLE 15
3 α ,5-dihydroxy-cholestane of the formula0.54 part of crude 3 α -acetoxy-4 α ,5-oxido-cholestane of the melting point 88-91° C. is dissolved in 20 parts by volume of dry ether, and the resultant solution then added dropwise and with thorough stirring to a solution of 0.54 part of lithium-aluminum hydride in 20 parts by volume of anhydrous ether. The reaction mixture is stirred for another 20 minutes, and then 10 parts by volume of water, followed by 10 parts by volume of 10% sulfuric acid, are carefully added thereto. After dilution with ether, the ethereal layer is washed with water and sodium bicarbonate solution, dried and evaporated. The residue, after recrystallization from alcohol, yields 3 α ,5-dihydroxy-cholestane of melting point 193-195° C.

EXAMPLE 16
3 β ,5-dihydroxy-cholestane of the formula0.13 part of 3 β -acetoxy-4 α ,5-oxido-cholestane of melting point 117° C. is reduced, in the same way as the 3 α -acetoxy-4 α ,5-oxido-cholestane of Example 15, with 0.13 part of lithium-aluminum hydride in absolute ether. Working up, as in the same example, yields a crystallized residue which melts at 223-225° C. and is 3 β ,5-dihydroxy-cholestane.

EXAMPLE 17
7 parts of Δ^{16} -3 β -acetoxy-14,15 β -oxido-20-keto-5 α -allo-pregnene are dissolved in 100 parts by volume of methanol and 50 parts by volume of chloroform, and the resultant solution is then added while stirring vigorously to a solution of 4 parts of sodium-boron hydride in 50 parts by volume of water and 100 parts by volume of dioxane. The reaction is carried out at 40° C. and the reaction mixture is then heated for 30 minutes to 50° C. Working up of the solid product is carried out after the manner of Example 6. The crude product is dissolved in 200 parts by volume of glacial acetic acid, and then oxidized in conventional manner in the cold with 3 parts of chromium trioxide. The resultant reaction product, after recrystallization from methanol, melts

at 149-150° C. and corresponds to the empirical formula C₂₃H₃₄O₄.

EXAMPLE 18

2 parts of crude Δ^4 -17,20-oxido-pregnene- α -(3) (isomeric mixture) of the melting point 177-188° C. are dissolved in 180 parts by volume of ether, and the resultant solution is then added dropwise and with thorough stirring to a solution of 2.2 parts of lithium-aluminum hydride in 120 parts by volume of absolute ether. After heating it for a short time, the reaction mixture is worked up in the manner described in Example 6. The resultant product, after recrystallization from methanol-water, melts at 150° C. It contains a double bond and two hydroxyl groups and yields a crystallized monoacetate.

In an analogous manner, there may also be reduced other 17,20-hydroxy-pregnanes, containing substituted or unsubstituted hydroxy groups, for example, in the 3- or in the 3- and 11- or 12-position.

Having thus disclosed the invention, what is claimed is:

1. A process for the preparation of a hydroxy steroid compound, which comprises subjecting the corresponding steroid vicinal epoxide to the reductive action of a member selected from the group consisting of alkali metal-aluminum hydride and alkali metal-boron hydride, as reducing agent, whereby reductive splitting of the epoxide group takes place.

2. A process according to claim 1, wherein the reducing agent is lithium-aluminum hydride.

3. A process according to claim 1, wherein the reducing agent is sodium-boron hydride.

4. A process according to claim 1, wherein the reducing agent is lithium-aluminum hydride, and the reduction is effected in an anhydrous, inert organic solvent.

5. A process for the preparation of a hydroxy steroid compound, which comprises subjecting the corresponding steroid vicinal 16,17-epoxide to the reductive action of a member selected from the group consisting of alkali metal-aluminum hydride and alkali metal-boron hydride, as re-

ducing agent, whereby reductive splitting of the epoxide group takes place.

6. A process for the preparation of a hydroxy steroid compound, which comprises subjecting the corresponding steroid vicinal 11,12-epoxide to the reductive action of a member selected from the group consisting of alkali metal-aluminum hydride and alkali metal-boron hydride, as reducing agent, whereby reductive splitting of the epoxide group takes place.

7. A process for the preparation of a hydroxy steroid compound, which comprises subjecting the corresponding steroid vicinal 14,15-epoxide to the reductive action of a member selected from the group consisting of alkali metal-aluminum hydride and alkali metal-boron hydride, as reducing agent, whereby reductive splitting of the epoxide group takes place.

8. A process for the preparation of a hydroxy steroid compound, which comprises subjecting the corresponding steroid vicinal 5,6-epoxide to the reductive action of a member selected from the group consisting of alkali metal-aluminum hydride and alkali metal-boron hydride, as reducing agent, whereby reductive splitting of the epoxide group takes place.

9. A process for the preparation of a hydroxy steroid compound, which comprises subjecting the corresponding steroid vicinal 17,20-epoxide to the reductive action of a member selected from the group consisting of alkali metal-aluminum hydride and alkali metal-boron hydride, as reducing agent, whereby reductive splitting of the epoxide group takes place.
